CLAIM

The ornamental design for a hat bill, as shown and described.

DESCRIPTION

FIG. 1 is a rear perspective view of a hat bill showing my new design;

FIG. 2 is a front elevational view thereof;

FIG. 3 is a left side elevational view thereof, the right side elevational view being a mirror image;

FIG. 4 is a rear elevational view thereof;

FIG. 5 is a top plan view thereof; and,

FIG. 6 is a bottom plan view thereof.

The phantom line portions of the above figures of the drawing are for illustrative purposes only and do not form part of the design claimed herein.
